INVENTOR.

UNITED STATES PATENT OFFICE.

JACOB CARON, OF NAMPA, IDAHO.

RAILROAD-TIE.

1,049,991.

Specification of Letters Patent.

Patented Jan. 7, 1913.

Application filed August 17, 1912. Serial No. 715,628.

To all whom it may concern:

Be it known that I, JACOB CARON, citizen of the United States, residing at Nampa, in the county of Canyon and State of Idaho, have invented certain new and useful Improvements in Railroad-Ties, of which the following is a specification, reference being had therein to the accompanying drawing.

This invention relates to railroad ties and has for its object the production of an efficient rail fastener which will efficiently hold the rail in a set position upon the tie so as to prevent the rail from pulling the spikes from the tie which would likely cause the derailment of a train passing over the rails.

Another object of the invention is the production of an efficient means for holding the rail fastening devices in engagement with the tie and rail whereby the rail fastening means will be prevented from becoming accidentally detached from the tie and rail.

With these and other objects in view this invention consists in certain novel combinations, constructions, and arrangement of parts as will be hereinafter fully described and claimed.

In the accompanying drawings:—Figure 1 is a top plan view of one end of the tie. Fig. 2 is a bottom plan view of one end of the stringer plate. Fig. 3 is a side elevation partly in section of the tie. Fig. 4 is a section taken on line 4—4, of Fig. 3. Fig. 5 is a detail perspective of the wedge member adapted to hold the rail gripping device in engagement with the rail and tie. Fig. 6 is a detail perspective of the spring member for holding the wedge shape member illustrated in Fig. 5 in its operative position. Fig. 7 is a detail perspective of the clamping member for holding the rail and tie together. Fig. 8 is a detail perspective of the pin used in connection with the wedge shape member and clamping member for holding the same against independent longitudinal movement.

By referring to the drawings it will be seen that 1 designates the tie which may be formed of the usual material and upon this tie is placed a stringer plate 2 preferably made of rolled metal. This stringer plate 2 is provided near each end with an upwardly extending thickened rail supporting portion 3 and directly below the rail supporting

portion is formed an integrally transversely extending slightly tapering rib 4, which rib is adapted to engage the tie 1 for holding the stringer plate 2 against longitudinal movement relative to the tie 1.

The stringer plate 2 is provided upon the thickened upwardly extending portions 3 thereof in spaced relation, with a pair of apertures for receiving the rail fastening devices 5. These apertures 5 are placed so as to be positioned upon each side of the base of the rail which is adapted to be supported upon the raised portion 3 of the stringer plate 2. These apertures 5 are provided with a beveled face 7 and upon the lower end of each of these apertures is formed a pocket 8 for receiving the laterally extending foot 9 of the rail gripping member 10. This rail gripping member 10 is provided with an overhanging head 11, which overhanging head is adapted to overhang the base of the rail as illustrated in Figs. 1 and 3. A wedge shape clamping member 12 is adapted to also fit in the aperture 5, and this wedge shape member fits between the rail clamping member 10 and the beveled face 7 of the aperture 5. It will, therefore, be seen that the rail gripping member 10 will be firmly clamped against the rail in the aperture 5 by driving the wedge shape clamping member 12 in the aperture 5 as illustrated in Fig. 3. It should be understood that each of the rail fastening devices is formed in the manner just described so as to firmly hold the rail in engagement with the stringer 2. Four of these devices are preferably employed as illustrated in Fig. 1.

The rail gripping member 10 is provided with a notched portion 13 upon its rear face and the wedge shape clamping member 12 is provided with a plurality of notches 14 upon its rear face. A square locking pin 15 is adapted to be forced in between the notch 13 in the gripping member 10 and one of the notches 14 formed in the clamping member 12. The ends of this pin may be bent over the edges of the gripping member 10 and the clamping member 12 so as to prevent the accidental displacement of the pin. It should be understood that through the medium of this locking pin 15 the locking member and clamping member will be held against independent longitudinal movement and thereby will be held in a tight position.

to prevent the accidental displacement of the rail fastener from the stringer as the train passes over the rails.

A spring member 16 is carried by the stringer so as to coöperate with each of the clamping members 12 thereby firmly holding the clamping members from becoming dislocated from their proper positions.

The stringer plate 2 is provided with a pair of rectangular sockets 17 placed in alignment with the apertures 5, and these rectangular sockets 17 terminate in circular sockets 18 formed upon the bottom of the stringer plate 2. Each of the spring members 16 is provided with a rectangular head 19, which when the same is being inserted in the sockets 17 is placed so as to have the head 19 extend longitudinal with the sockets 17 for facilitating the placing of the spring 16 in its operative position. The spring 16 while being placed in the socket 17 will extend transversely of the tie. As soon as the head 19 is placed in the socket 17 so as to register with the socket 18 the spring 16 is then rotated so as to have the outer end 20 overhang the upper end of the wedge shape clamping member 12. The spring 16 has its outer end 20 bent upwardly, and this outer end 20 is so formed as to constitute a pocket 21 for fitting snugly over the head of the wedge shape clamping member 12 so as to prevent the accidental rotation of the spring 16 after the same has once been placed upon the tie so as to overhang the wedge shape clamping member. It should be understood that by means of the locking devices for the spring 16 as above set forth and as illustrated in Fig. 3 the spring 16 will be held against accidental removal from the tie, and the wedge shape clamping member 12 will also be held in its correct position even though the pin 15 becomes accidentally removed from the locking member 10 and clamping member 12. By means of the present shielding device, to wit:—the spring 16 it will be seen that if the spring 16 should become accidentally broken or worn the same may be readily removed and a new spring placed in its place. By means of the present stringer as illustrated and described it will be seen that a smooth surface is present throughout the entire length of the tie where no integral protruding lugs are produced which might become accidentally broken off.

It will be noted that by carefully considering Figs. 3 and 6 that the spring member 16 is provided with a rearwardly extending

bulged portion 22, which bulged portion engages near its lower end the edge of the aperture 17, and provided the spring member 16 should be lifted upwardly at its outer end the spring would be greatly reinforced owing to the fact that the edge of the aperture 17 bears against the spring at its rear end as illustrated in Fig. 3.

Having thus described the invention what is claimed as new, is:—

1. A device of the class described comprising a base, a plate carried by said base, rail fastening means carried by said plate, said rail fastening means comprising a clamping member and a gripping member, means for holding said clamping member and gripping member in a locked position, a spring clamping member, said plate provided with a plurality of spring clamping receiving sockets, each clamping receiving socket constituting an elongated rectangular socket terminating at its bottom in a circular recess, each spring clamping member provided with an elongated head at its bottom end adapted to be inserted in said elongated sockets and rotated within said recesses whereby said elongated head will be held against accidental removal from said sockets, said spring clamping member provided with an overhanging spring portion having an off-set head, said head bent to constitute a pocket for fitting over said clamping member whereby said clamping member will be held against removal from said plate, said spring member provided with a bulged rear end for constituting a downward pressure upon the free end of said spring clamping member.

2. A device of the class described comprising a base, said base provided with a plurality of sockets substantially rectangular terminating in circular openings, a spring clamping member adapted to fit in each socket comprising a body, said body terminating in a depending body provided with laterally extending lugs, said lugs adapted to pass down through said rectangular slot, and said depending end adapted to be rotated within said rectangular slot for causing said lugs to extend laterally over said slot within said circular opening.

In testimony whereof I hereunto affix my signature in presence of two witnesses.

JACOB CARON.
